UNITED STATES PATENT OFFICE.

ABRAMO CAVALLARO, OF DETROIT, MICHIGAN.

DESIGN FOR A LAMP.

Application filed April 20, 1927. Serial No. 21,647. Term of patent $3\frac{1}{2}$ years.

To all whom it may concern:

Be it known that I, ABRAMO CAVALLARO, a subject of the King of Italy, residing at Detroit, in the county of Wayne and State of Michigan, have invented a new, original, and ornamental Design for Lamps, of which the following is a specification, reference being had to the accompanying drawing, forming part thereof.

Fig. 1 is a side view of a lamp embodying my invention.

Fig. 2 is a plan view thereof.

I claim:

The ornamental design for a lamp as shown.

ABRAMO CAVALLARO.
